UNITED STATES PATENT OFFICE.

ALOIS WEINBACHER, OF OSHKOSH, WISCONSIN.

CARPENTER'S KNIFE.

1,323,937.

Specification of Letters Patent.

Patented Dec. 2, 1919.

Application filed May 21, 1919. Serial No. 298,704.

To all whom it may concern:

Be it known that I, ALOIS WEINBACHER, a citizen of the United States, residing at Oshkosh, county of Winnebago, and State 5 of Wisconsin, have invented certain new and useful Improvements in Carpenters' Knives, of which the following is a specification.

This invention relates to a combination cutting tool for use by carpenters, cabinet makers and woodworkers generally and it has for an object to provide a tool presenting a single cutting edge which can be used efficiently in a variety of ways and particularly as a chisel and a draw knife, not only when the latter are ordinarily used, but on work when the use of such instruments is desirable but the application of an ordinary tool thereto impossible.

20 The invention has for a further object to provide a tool of this nature characterized by cheapness, ease of keeping in condition, and lightness in proportion to the work capable of being done.

25 For further comprehension of the invention, and of the objects and advantages thereof, reference will be had to the following specification and accompanying drawings, and to the appended claim in which 30 the novel features of the invention are more particularly set forth.

Figure 1 of the drawings is a perspective view of a cutting tool constructed according to my invention.

35 Fig. 2 is a rear edge view thereof.

Fig. 3 is a transverse section on the line 3-3 of Fig. 2.

40 My improved tool comprises a relatively long shank bar 1 of comparatively small cross section and of oblong shape in cross section and inserted at one end in a handle 2 in the usual manner, both the handle and the manner of securing the tool therein being ordinary.

45 The outer end of the bar is provided with a triangular cutting head 3 in the form of a lateral offset, this triangular head tapering outwardly on both sides from the point of meeting with the bar as at 4 and 50 5 to form a straight cutting edge 6 along the third side, the side 4 being a continuation of the outer edge of the bar 1.

55 This third side is approximately double the length of 5 and they form at their apex 7 a right angle, the cutting edge 6 extending in the median line of the shank bar and at an acute angle thereto.

As a consequence of this construction the tool presents in a single cutting edge a relatively fine portion adjacent the extreme 60 point 8 of the tool which renders it peculiarly adapted for a drawing or pulling stroke to replace a draw knife and remove finely shaved portions of wood, while adjacent the point a stouter cutting portion is 65 formed which readily performs the work of a chisel, the combination being arranged to permit of use such as in corners or adjacent the meeting angles of a pair of vertically disposed surfaces, where an ordinary chisel 70 or draw knife cannot be employed. For instance, the tool may be employed as a draw knife and moved along the work in the general direction of the arrow A as in Fig. 1 permitting it to work close in to a vertical 75 surface without interference of said surface with the proper handling of the operator, or it may be used as a chisel and moved along the work in the general direction of the arrow B in Fig. 1 likewise permitting 80 free manipulation close to a vertical surface.

The disposition of the cutting head also facilitates an oblique stroke along the work with a consequent increased ease of cutting 85 permitting the use of a relatively light tool on comparatively heavy work.

The tool may also be used in cleaning out grooves or like work the pointed ends facilitating work of this kind.

Having thus described my invention and 90 set forth the manner of its use, what I claim as new and desire to secure by Letters Patent, is:-

A combination cutting tool for woodworkers comprising a shank bar having a 95 triangular cutting head, one side of which is flush with one edge of the bar, said head having a second relatively short side extending at an angle to the bar, and a third relatively long side extending at a lesser 100 angle to the bar than the said short side, said head tapering evenly in thickness from the point of juncture with the bar both longitudinally and transversely of the bar and forming a straight-edged cutting element presenting an increasingly heavy cutting portion rearwardly from the extreme point of the tool.

In testimony whereof I have affixed my signature.

ALOIS WEINBACHER.
